UNITED STATES PATENT OFFICE.

HARRY E. TOWNSEND, OF BROOKLYN, NEW YORK, ASSIGNOR TO THE ANCHOR CAP & CLOSURE CORPORATION, OF BROOKLYN, NEW YORK, A CORPORATION OF NEW YORK.

SIDE SEAL FOR GLASS CONTAINERS AND THE LIKE.

1,242,743.

Specification of Letters Patent.

Patented Oct. 9, 1917.

Application filed January 10, 1917. Serial No. 141,552.

To all whom it may concern:

Be it known that I, HARRY E. TOWNSEND, a citizen of the United States, and a resident of the city of Brooklyn, in the county 5 of Kings, State of New York, have invented certain new and useful Improvements in Side Seals for Glass Containers and the like, of which the following is a specification.

This invention relates to sealing closures 10 adapted to be applied to glass containers and the like and has particular reference to the type of closure disclosed in my prior Patent No. 1,159,624, granted Nov. 9, 1915, upon which this invention constitutes an 15 improvement. In this type of closure the seal is effected against the side wall of the container by compression of the gasket so that the gasket is squeezed laterally against the container wall.

20 The objects of this invention include the provision of a closure of the character specified, and wherein the amount of power for sealing is reduced, as well as the glass breakage, and wherein the latitude of variation 25 of the sizes of glass containers is increased, and also wherein a better and more effective seal is provided.

These various improvements may be accomplished by producing the seal with a 30 smaller cross-sectional area in the bead portion of the seal and providing a short depending skirt adjacent the bead, which skirt is slightly inclined or is substantially parallel to the side wall of the container, 35 thereby compressing the gasket against the side wall in such manner as to provide a larger sealing surface with the glass, and wherein substantially all of which surface is supported by the deformed metal portion 40 of the closure.

Figure 1 illustrates in elevation the closure applied to a glass container such as a tumbler.

Fig. 2 is a detail view illustrating a section through a portion of the closure and the work faces of the sealing jaws prior to the sealing operation.

Fig. 3 is a detail view showing in section a portion of the closure and sealing jaws at 50 the completion of the sealing operation.

In the prior art referred to the lower edge of the gasket is substantially unsupported, the seal being effected between the horn-shaped portion of the bead, the upper side 55 wall of the said bead, and the side wall of

the glass. In the present invention the seal is likewise effected between the horn-shaped portion of the bead, the upper side wall thereof, to which is added the very material benefit of the depending skirt 60 which very tightly compresses the gasket directly against the side wall of the glass.

By forming the horn portion of the bead smaller, the deforming surface area of the die is reduced and since the skirt portion 65 comprises metal which is bent or flowed over the deforming portion of the die, the formation of the skirt portion requires relatively little power, as compared with the prior closures, so far as the closing power of the 70 chucks or dies is concerned, and at the same time the lateral forces produced by the gasket material being squeezed inwardly in forming the horn portion are fully conserved 75 by being firmly supported by the skirt.

The fact that a wider surface or sealing area is provided by this closure enables this closure to be used successfully on glass containers having considerable relative variation in sizes. This has the effect of reducing breakage and also of increasing the 80 effectiveness of the seals formed.

Referring now to the drawings, the glass container 1, may if desired be provided with a cylindrical sealing surface 2 adjacent the 85 mouth of the container. The closure cap is provided with a top or cover portion 4 which carries an annular beading having walls 5 and 6 and preferably with slightly inturned lower edges 7. This beading is 90 preferably spaced slightly below the cover portion 5 as by means of a depending wall 8, in order that the seal may be made slightly below the upper edge of the glass container which in most cases contains the greatest 95 amount of irregularities. The immediate foregoing description refers to the closure before the seal is formed.

A pair of forming dies comprising an anvil member 9 having an annular cup 100 shaped ring 10 and a cylindrical wall 11 formed in the lower portion thereof is adapted to coöperate with a chuck member 12 provided with an annular bead 14. Suitable mechanism, as for example, the structure disclosed in the patent to Hull No. 1,134,065, is provided for operating the dies, so that the closing of the forming jaws causes the metal to assume the shape illustrated in Fig. 3 wherein the gasket 15 is 110

forced inwardly and spread out against the side wall of the container to provide a finished closure having a horn shaped portion 16 which provides a suitable receptacle for sufficient body of the gasket to enable the resiliency thereof to maintain sealing pressure against the side walls of the glass even though there may be considerable variation in sizes of the glass. The depending skirt 17 below the horn shaped portion supports the portion of the gasket flowed out of the horn shaped portion 16 and thus comprises an annular band beneath which the gasket member is under considerable pressure. In view of the fact that a portion of the gasket while being laterally supported is permitted to escape outwardly and downwardly, as at 18, less sealing force is required in making this seal than wherein the gasket is retained in a relatively restricted space.

Having thus described my invention what I claim is:—

1. A closure for sealing on a substantially cylindrical side wall and provided with an annular beading and a gasket held under compression between opposing walls of the beading with a portion of said gasket displaced laterally under said compression against the substantially cylindrical wall of the container, the said beading having a horn-shaped cross-section increasing in area inwardly, and a depending annular skirt extending downwardly from said horn-shaped portion and retaining the lower portion of said gasket under compression.

2. A closure provided with an annular beading and a gasket under compression between opposing walls of the beading with a portion of said gasket displaced laterally under said compression against the wall of the container, the beading having its upper wall in the form of a concave surface and the opposing wall in the form of a convex surface, the two walls being so related that

the cross-sectional area of the beading increases inwardly and downwardly, and an annular skirt depending from said convex surface, said annular skirt being constructed to support the lower edge of said gasket.

3. A closure comprising, in combination, a container, a cap provided with a top portion and a depending side portion; said side portion including an annular bead having a groove in the upper side thereof to form a concave portion, a fold adjacent said concave portion, a convex ring extending below the said fold, an annular skirt beneath said convex ring; and a suitable gasket maintained under pressure between said depending side portion and the side wall of said container with the upper and lower portions of the gasket under greater compression than the middle portion.

4. A closure comprising, in combination, a container, a cap having a top adapted to fit over said container, a side wall extending downwardly over the side wall of said container, said side wall being provided with a bead including an annular fold of metal, a skirt depending from said bead, and a suitable gasket retained under pressure between said bead said skirt and the side wall of said container with the upper and lower portions of the gasket under greater compression than the middle portion.

5. In a closure, in combination, a container, a cap having a top portion and side portions extending downwardly over the mouth of said container, the side portion of the cap comprising an annular bead, a skirt depending from said annular bead, and a suitable gasket constructed to be maintained under pressure between the side wall of the container the annular bead and the said skirt with the upper and lower portions under greater compression than the middle portion.

HARRY E. TOWNSEND.
